UNITED STATES PATENT OFFICE.

ROBERT S. FRAM, OF VANDALIA, ILLINOIS.

BEATING-ENGINE.

1,103,280.

Specification of Letters Patent. Patented July 14, 1914.

Application filed February 6, 1913. Serial No. 746,533.

To all whom it may concern:

Be it known that I, ROBERT S. FRAM, a citizen of the United States, residing at Vandalia, in the county of Fayette and State of Illinois, have invented certain new and useful Improvements in Beating-Engines, of which the following is a specification.

The present invention relates to improvements in beating engines of the type used for treating or reducing fibrous material to a finely comminuted mass, as is required in the manufacture of paper or other analogous products.

The primary object of the invention is the provision of means for raising or lowering, by power, the supporting means for the beating drum or roll.

In the operation of beating engines acting upon rags and other materials in the manufacture of paper, when the vat or tank is first charged, the roll or drum is raised to a predetermined maximum height above the bed plate. As the material is comminuted, the beating drum is gradually lowered, to more finally reduce the mass. To accomplish this purpose I have combined and arranged the hereinafter described mechanisms in novel forms to increase the efficiency of the machine, and to save time and labor.

In the accompanying drawings I have illustrated one complete example of the physical embodiment of my invention constructed according to the best mode I have so far devised for the practical application of the principles of the invention.

Figure 1. is a top plan view of a beating engine involving my novel construction. Fig. 2 is an end view of so much of the mechanism of Fig. 1 as is necessary to illustrate the invention. Fig. 3 is a plan view of part of the mechanism of Fig. 1, enlarged.

In the preferred embodiment of my invention as illustrated in the drawings I utilize the usual drum or vat 1 having the central or mid-feather 2 around which the stock passes as usual.

In Fig. 1, under the cover or housing 4 the shaft 5 extends, and at its ends is supported in the suspension bearing arms 6, 6, which are pivoted or hinged at 7 in the frame 8.

A counter shaft 9 is arranged parallel with the main shaft, the latter being driven through the medium of the pulley 10, and the counter shaft is driven from the main

shaft, through the medium of the open belt 11 or the crossed belt 12 as desired. For rotating the countershaft from the open belt a clutch member 13 is revolute loosely on the countershaft, and for revolving the countershaft in a reverse direction, the clutch member 14 is employed. These clutch members are actuated through the medium of the friction clutch spool 15 which is keyed to the countershaft, and may be shifted through the forked lever 15' and shift rod 16. At each end of the countershaft 9 it is provided with a worm screw 17 and the ends of the shaft are supported in bearing brackets 18 supported from the post 19 of the supporting frame.

A horizontally revolute worm wheel 20 is arranged adjacent to and meshes with each worm 17. Each wheel has a hub 25, 75 which is held by a pin 24, against dislocation in a vertical direction, but is permitted to revolve in a horizontal plane. A vertical, adjusting screw bar 21 is provided for each wheel and this bar may be raised or lowered 80 through the action of its wheel.

At its lower end the bar is provided with a hook 22, complementary to the hook 23 on the end of the arm 6 and by means of the hook on the bar the free end of the pivoted 85 arm is suspended.

An indicating device is provided, to show the height of the beating drum, and for this purpose a pointer 26 located on the screw bar coacts with a pointer 27 which, through 90 the medium of the holder or sleeve 28 and screw 29, is held in adjusted position on the rod 30 which is fixed on the frame of the engine.

The mode of operation will be evident, 95 and an extended description is unnecessary. When it is desired to adjust the position of the beating drum, the pointer 27 is moved to a predetermined position on the rod or post 30, and the position of the drum may 100 be determined thereafter by the relationship of the pointer 26 and pointer 27. To raise the drum, the clutch member 11 is engaged by the spool 15, and the countershaft is revolved. The revolution of this shaft revolves the worm screws, the worm wheel, and through the worm wheel (which revolves) the screw bar is drawn up carrying with it the arms 6. To lower the drum, the clutch 13 is thrown out and the clutch 14 is engaged, and the crossed belt reverses 110 the movement of the parts.

Having thus described my invention, what I claim as new is:—

In a beating engine, the combination with its frame, drum, main shaft and pivoted shaft supporting arms, suspension means for the free ends of said arms, a countershaft and two pulleys thereon driven from the main shaft, a clutch on the countershaft, for engaging either pulley, and means actuated

from the countershaft for elevating or depressing said arms. 10

In testimony whereof I affix my signature in presence of two witnesses.

ROBERT S. FRAM.
